CHANGEABLE LETTER DISPLAY APPARATUS
 Glenn A. Offenbauer, Palmetto, Fla., assignor to Florida
 Plastics, Inc., Palmetto, Fla., a corporation of Florida
 Filed Dec. 1, 1964, Ser. No. 414,990
 1 Claim. (Cl. 40—143)

The present invention relates to a changeable letter arrangement adapted to be used with perforated boards or sheets or standard pegboard.

Pegboard has been an adaptable item of multifaceted utility and has in the past even been adapted for the display of letters, signs and symbols.

In the past complicated arrangements have been made for such display requiring complicated holding means and holding devices. Also, letter displays have been provided, depending upon complicated or expensive board structure.

According to the present invention, a versatile inexpensive hook and pin assembly is provided, allowing for stability of display, ease in preparation for use and ease in mounting and dismounting.

Although such novel feature or features believed to be characteristic of the invention are pointed out in the claim, the invention and the manner in which it may be carried out may be further understood by reference to the description following and the accompanying drawings.

FIG. 1 is a front elevation of a display of letters of the present invention.

FIG. 2 is a section of FIG. 1 at lines 2—2.

FIG. 3 is a section of FIG. 1 at lines 3—3.

FIG. 4 is a section of FIG. 1 at lines 4—4.

FIG. 5 is a detail of a hook of the present invention.

FIG. 6 is a detail of a pin of the present invention.

Referring now to the figures in greater detail, where like reference numbers denote like parts in the various figures.

The present invention is a new combination of letters 1 or other symbols adapted to be mounted on a pegboard 2.

Usual pegboard 2 comprises a fibre board of hardened fibre with regularly spaced openings 3, illustrated in detail in FIG. 1, the balance of such openings 3 at the marked points 4 as shown in FIG. 1.

The letters 1 each include at least one hook 5 and preferably at least one pin 6.

The letters 1, hooks 5 and pins 6 are preferably of plastic and may come as a kit including hooks and pins 6 mounting means such as cement or means to thermoplastically bond the hooks 5 and pins 6 to the letters 1 at appropriate points.

The hook 5 comprises a rounded portion 7 whose outer surface completes an arc of about a quarter circle. The rounded portion has a diameter just somewhat smaller than that of the openings 3. The rounded portion 7 ends at a wider portion 8 which extends from a mounting base 9. The hook 5 may be integral to a letter 1 or may be separately mounted spaced to fit letters on a board as shown in FIG. 1. The mounting of the hook 5 may be by conventional means such as cement or thermoplastic welding. While the outer diametric measurements of the rounded portion 7 should be smaller than the openings 3, the rounded portions may have a round, flat or a square cross-sectional configuration or other without changing the effect of the present invention.

The inside surface 10 of the hook 5 between the rounded portion 7 and the wider portion 8 is preferably flat and of a length generally to coincide with the thickness of usual pegboard 2.

The pin 6 has a protrusion 11 preferably of a diameter just smaller than the pegboard opening 3 and usually of a round configuration. The protrusion

usually extends about the thickness of the pegboard 2 and ends as a flared collar 12 extending from a portion 13 wider than the protuberance 11 which is mounted on a base 14.

5 The pin 6 may be integral to the letter 1 or joined to it in the same manner as the hook 5.

The pin 6 or pins 6 depending upon the needs of the letter 1 to be mounted, must be spaced so that they are coincidental with the pegboard openings 3 when a letter 1 is mounted.

10 In use a letter 1 to be mounted is provided with an appropriately placed hook 5 or hooks 5 and pin 6 or pins. Where a plurality of hooks 5 are provided such hooks 5 must be parallel to each other and spaced to coincide with the openings 3.

A letter 1 to be mounted is placed at an angle with the hook 5 engaging an opening 3 as shown in FIG. 3 and then rotated downward into the opening. The inner surface 10 of the hook 5, the rounded portion 7 and the

20 wider portion 8 form a snug fit of the letter 1 and hook 5 on the pegboard 2 making the letter 1 unremovable from the pegboard 2 unless rotated up again and slipped out.

The pin 6 protrusion 11 snugly engages the opening 25 3 holding the bottom portion of the letter 1 spaced away from the pegboard 2 and firm against lateral movement.

It is preferable that the distances between the wider portion 8 of the hook 5 and the letter 1 and the collar 12 of the pin 6 and the letter be approximately equal 30 so that the letters 1 are mounted parallel to the surface of the pegboard 2.

Where letters 1 with peripheral flanges (not shown) are used, the length of the wider portion 8 of the hook 5 and the portion 13 of the pin 6 may be adapted accordingly to permit proper affixation of the letters 1 spaced from the pegboard 2.

While the bases 9, 14 of the hook 5 and pin 6 have been shown in a specific configuration, their shapes are not crucial as long as they are able to form a proper 40 mount to the letters 1.

The hooks 5 and pins 6 are preferably plastic molded and supplied separate of the letters so the user can select the desired number of hooks 5 and pins 6 for appropriate mounting of letters 1, using means aforementioned.

45 Typical hook 5 and pin 6 placements can be seen dotted with regard to the different letters 1 as shown in FIG. 1.

The terms and expressions which are employed are used as terms of description, it is recognized, though, that various modifications are possible within the scope of the invention claimed.

Having thus described certain forms of the invention in some detail, what is claimed is:

50 A plastic pegboard mountable article of manufacture comprising a letter, said letter including at least one hook; each hook including; a curved portion; said curved portion smaller than the diameter of a pegboard opening, the outer surface of said curved portion having an arc of approximately a quarter circle; another portion extending beyond said curved portion, said extending portion having a diameter greater than the diameter of said pegboard opening; a base; said curved portion and extending portion mounted on said base; said base affixed to said letter mountable on said pegboard, at least one pin; each pin 55 including a protuberance smaller than the diameter of a pegboard opening; a portion extending beyond said protuberance, said extending portion having a diameter greater than the diameter of said pegboard opening; a base; said extending portion mounted on said base; said base affixed to said letter mountable on said pegboard, and said hook and pin spaced apart on said letter and

adapted to fit into the openings in a pegboard whereby said extending portions co-act to maintain said letter at a predetermined distance from and parallel to said pegboard.
